DRAPERY TIEBACK

Emily J. McKee, Richmond, Ind.

Application December 21, 1949, Serial No. 6,753

Term of patent 3½ years

(Cl. D21—1)

To all whom it may concern:

Be it known that I, Emily J. McKee, a citizen of the United States, residing at Richmond, in the county of Wayne and State of Indiana, have invented a new, original, and ornamental Design for a Drapery Tieback, of which the following is a specification, reference being had to the accompanying drawing, forming a part hereof.

Fig. 1 is an elevational view of a drapery tieback showing my new design, and

Fig. 2 is a sectional view taken on the line 2—2 of Fig. 1 showing the convexity of the ornament and its bracket support.

I claim:

The ornamental design for a drapery tieback, as shown.

EMILY J. MCKEE.
